UNITED STATES PATENT OFFICE.

SAMUEL BISHOP, OF DOBBINS, CALIFORNIA.

SIGHT FOR GUNS.

968,115.

Specification of Letters Patent. Patented Aug. 23, 1910.

Application filed March 20, 1909. Serial No. 484,676.

To all whom it may concern:

Be it known that I, SAMUEL BISHOP, a citizen of the United States, residing at Dobbins, in the county of Yuba and State of California, have invented a new and useful Improvement in Sights for Guns, of which the following is a specification.

This invention relates to a gun sight and the object of the invention is a device of 10 this kind in which the peep or guide will not throw a shadow upon the bead and a further object of the invention is to combine the peep and bead upon a common base.

The invention consists of the novel features of construction hereinafter described, 15 pointed out in the claims and shown in the accompanying drawings, in which—

Figure 1 is a perspective view showing the sight applied, a gun barrel being broken 20 away. Fig. 2 is a cross section through a gun barrel, showing the sight in elevation from the rear. Fig. 3 is a perspective view of the sight detached.

In the drawing, 1 represents a longitudinally extending base which carries a dove-tail wedge block 2 upon its under surface, which block fits into a dove-tail recess and transversely into a block 3 secured longitudinally upon the gun barrel. At the rear 30 of the base 1 is a circular ring 4 forming a peep and upon the front end of said base is mounted a shank 5 triangular in vertical cross section, and mounted upon said shank is a tapering bead 6, the rear end of which 35 projects beyond the shank 5, said rear end

terminating in a flat circular face, the said bead tapering from the top of said rear face downwardly and forwardly to the front end of the shank. The bead is formed of either gold or ivory and the base 1 is of a sufficient 40 length to prevent the ring 5 from casting a shadow upon the rear end of the bead, or darkening the object aimed at.

The entire sight is readily detachable from the gun barrel and may be as easily 45 replaced.

What I claim is:—

1. The combination with a gun barrel, of a longitudinal base arranged thereon, a ring mounted upon the rear end of said base, a 50 shank mounted upon the front end of said base and a tapering bead having a flat circular rear end, said bead being mounted longitudinally upon said shank.

2. A device of the kind described comprising a flat base, means for detachably connecting said base to a gun barrel, a ring carried by one end of the base, a shank triangular in cross section mounted upon the opposite end of the base, the said ring having 55 a diameter greater than the height of the shank, and a tapering bead arranged longitudinally upon said shank, said bead having a flat circular rear face, each portion of said face lying in the same plane. 60 65

SAMUEL BISHOP.
